[57] CLAIM

The ornamental design for a child's wash basin, as shown and described.

DESCRIPTION

FIG. 1 is a perspective view taken from the top, rear and left side of a child's wash basin showing my new design;

FIG. 2 is a perspective view taken from the bottom, front and left side thereof;

FIG. 3 is a left side elevational view thereof, the right side being a mirror image of the left side shown; and FIG. 4 is a top plan view thereof.
